In Great Britain July 24, 1945

10 Claims. (Cl. 80—6)

1

This invention relates to the rolling of screw threads upon blanks by means of pairs of hardened rolls having peripheral threads on their surfaces. In machines for this purpose, the blank is interposed between the two rolls and the metal of the blank is displaced to form threads of the desired depth and pitch without removal of metal.

In machines as at present constructed, either one roll advances toward the other while the thread is rolled into the blank, or the blank is caused to pass laterally into and through the gap between the rolls which are set at such a distance apart that a thread of the required form and depth is impressed upon the blank as it passes into and through the gap. In the latter case, controlled travel of the blank into and through the gap is provided by making one of the rolls slightly greater in diameter than the other, while driving both rolls at the same speed of rotation, in order that the difference in circumferential speed of the larger roll may control the movement of the blank into and past the gap when the blank is gripped by the rolls. In such machines, the blank, after passing through the narrowest gaps between the rolls, continues to move away from the gap at the speed with which it entered, until it falls free of the rolls, but it is liable to be damaged by continuing contact with the threads of the rolls and it is an object of the invention to avoid this. With this object in view, the invention is designed to provide for the rapid ejection of the rolled blank immediately after passing through the narrowest portion or center of the gap by imparting a longitudinal movement to one of the rolls relatively to the other whereby a rolled blank is automatically ejected by its engagement with the threads on the rolls. Other objects are to provide for the accurate adjustment of the rolls and their shafts, for variation of the setting of the rolls when operating upon blanks of different sizes, for the feed of the blanks to the gaps between the rolls, and for control of all the movements of the parts so that the operations may be as automatic as is desired. An ultimate object is to render the whole operation of the machine automatic so that blanks are introduced, rolled and ejected in regular sequence.

A convenient form of the machine for carrying the invention into effect is illustrated in the accompanying drawings, in which:

Figure 1 is an end elevation, partly in section, of the complete machine;

Figure 2 is a vertical section on the line II—II of Figure 1;

Figure 3 is a plan view partly in section on the line III—III of Figure 1;

Figures 4A and 4B, taken together, show, on an enlarged scale, the principal operating parts of the machine, in section on the line IV—IV of Figure 3;

2

Figure 5 shows the driving gear for the roll shafts in section on the line V—V of Figure 4B;

Figure 6 is an end view, partly in section and on an enlarged scale, of the blank feeding and thread-forming mechanism;

Figure 7 is a diagram of the electric and hydraulic circuits used in the control of the machine.

Referring to the drawings, the machine shown 10 has a base casting 10 on which is carried an upper casting 11 supporting the main operating parts. The base casting 10 carries at one end an electric motor 12, whose shaft carries a stepped pulley 13 driving, through belt 16, a stepped pulley 14 on shaft 15. This shaft drives, through gearing in casing 17, a worm 18 meshing with worm wheel 19 on upright shaft 20. The shaft 20 drives the two horizontal shafts 21 and 22 carrying the rolls 23 and 24, respectively, for rolling the threads 15 into the blanks 25. As shown in Figure 5, the vertical shaft 20 is supported in ball bearings 26, 27, 28, 29 and 30, and has a worm 31 keyed on it and driving worm wheel 32 on shaft 21. As shaft 22 is adjustable up and down with respect to 20 shaft 21, the worm 33 driving worm wheel 34 on shaft 22 works on splines 35 on the upper part of shaft 20, allowing it to rise and fall with the housing 36 which accommodates the worm 33, worm wheel 34 and shaft 22. The housing 36 is carried by a slide 37, which works over dovetailed guide surfaces in a column 38, and can be adjusted in height by a hand wheel 39, actuating a worm 40 in head 41. This worm 40 engages with worm wheel 41, keyed to a nut 43, which engages a heavy screw 42 whose lower end is secured to the slide 37, as best seen in Figure 4A. A long taper wedge 46, with a fine adjustment at 44 on the slide, as shown in dotted lines in this figure, enables any slack to be taken up in the guide surfaces, the wedge being clamped after adjustment by a screw 45 engaging in a slot in the slide. The worm 41 and nut 43 are carried in a head 47 secured by bolts 48 to the top of column 38, and by bolts 49 to another column 50, both columns 38 and 50 being mounted on the casting 11. The slide 37 is locked in its adjusted positions by bolts 51 extending through slots at 45 52 in the column 38.

Referring to Figures 4A and 4B, the worm wheels 32 and 34 are both splined on their shafts 21 and 22, respectively, and are mounted in ball bearings 53 and 54 in their housings. The shaft 22 is locked against longitudinal movement by collar 55 and nuts 56 at either side of the worm wheel 34. At its end which carries the threaded roll 24, the shaft 22 is of larger diameter and is supported by a roller bearing 57, its projecting end being carried in another roller bearing 58 in a detachable bracket 59 secured by bolts 60 to 50 the slide 37. The elements 41, 43, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 580, 581, 582, 583, 584, 585, 586, 587, 588, 589, 590, 591, 592, 593, 594, 595, 596, 597, 598, 599, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 610, 611, 612, 613, 614, 615, 616, 617, 618, 619, 620, 621, 622, 623, 624, 625, 626, 627, 628, 629, 620, 621, 622, 623, 624, 625, 626, 627, 628, 629, 630, 631, 632, 633, 634, 635, 636, 637, 638, 639, 630, 631, 632, 633, 634, 635, 636, 637, 638, 639, 640, 641, 642, 643, 644, 645, 646, 647, 648, 649, 640, 641, 642, 643, 644, 645, 646, 647, 648, 649, 650, 651, 652, 653, 654, 655, 656, 657, 658, 659, 650, 651, 652, 653, 654, 655, 656, 657, 658, 659, 660, 661, 662, 663, 664, 665, 666, 667, 668, 669, 660, 661, 662, 663, 664, 665, 666, 667, 668, 669, 670, 671, 672, 673, 674, 675, 676, 677, 678, 679, 670, 671, 672, 673, 674, 675, 676, 677, 678, 679, 680, 681, 682, 683, 684, 685, 686, 687, 688, 689, 680, 681, 682, 683, 684, 685, 686, 687, 688, 689, 690, 691, 692, 693, 694, 695, 696, 697, 698, 699, 690, 691, 692, 693, 694, 695, 696, 697, 698, 699, 700, 701, 702, 703, 704, 705, 706, 707, 708, 709, 700, 701, 702, 703, 704, 705, 706, 707, 708, 709, 710, 711, 712, 713, 714, 715, 716, 717, 718, 719, 710, 711, 712, 713, 714, 715, 716, 717, 718, 719, 720, 721, 722, 723, 724, 725, 726, 727, 728, 729, 720, 721, 722, 723, 724, 725, 726, 727, 728, 729, 730, 731, 732, 733, 734, 735, 736, 737, 738, 739, 730, 731, 732, 733, 734, 735, 736, 737, 738, 739, 740, 741, 742, 743, 744, 745, 746, 747, 748, 749, 740, 741, 742, 743, 744, 745, 746, 747, 748, 749, 750, 751, 752, 753, 754, 755, 756, 757, 758, 759, 750, 751, 752, 753, 754, 755, 756, 757, 758, 759, 760, 761, 762, 763, 764, 765, 766, 767, 768, 769, 760, 761, 762, 763, 764, 765, 766, 767, 768, 769, 770, 771, 772, 773, 774, 775, 776, 777, 778, 779, 770, 771, 772, 773, 774, 775, 776, 777, 778, 779, 780, 781, 782, 783, 784, 785, 786, 787, 788, 789, 780, 781, 782, 783, 784, 785, 786, 787, 788, 789, 790, 791, 792, 793, 794, 795, 796, 797, 798, 799, 790, 791, 792, 793, 794, 795, 796, 797, 798, 799, 800, 801, 802, 803, 804, 805, 806, 807, 808, 809, 800, 801, 802, 803, 804, 805, 806, 807, 808, 809, 810, 811, 812, 813, 814, 815, 816, 817, 818, 819, 810, 811, 812, 813, 814, 815, 816, 817, 818, 819, 820, 821, 822, 823, 824, 825, 826, 827, 828, 829, 820, 821, 822, 823, 824, 825, 826, 827, 828, 829, 830, 831, 832, 833, 834, 835, 836, 837, 838, 839, 830, 831, 832, 833, 834, 835, 836, 837, 838, 839, 840, 841, 842, 843, 844, 845, 846, 847, 848, 849, 840, 841, 842, 843, 844, 845, 846, 847, 848, 849, 850, 851, 852, 853, 854, 855, 856, 857, 858, 859, 850, 851, 852, 853, 854, 855, 856, 857, 858, 859, 860, 861, 862, 863, 864, 865, 866, 867, 868, 869, 860, 861, 862, 863, 864, 865, 866, 867, 868, 869, 870, 871, 872, 873, 874, 875, 876, 877, 878, 879, 870, 871, 872, 873, 874, 875, 876, 877, 878, 879, 880, 881, 882, 883, 884, 885, 886, 887, 888, 889, 880, 881, 882, 883, 884, 885, 886, 887, 888, 889, 890, 891, 892, 893, 894, 895, 896, 897, 898, 899, 890, 891, 892, 893, 894, 895, 896, 897, 898, 899, 900, 901, 902, 903, 904, 905, 906, 907, 908, 909, 900, 901, 902, 903, 904, 905, 906, 907, 908, 909, 910, 911, 912, 913, 914, 915, 916, 917, 918, 919, 910, 911, 912, 913, 914, 915, 916, 917, 918, 919, 920, 921, 922, 923, 924, 925, 926, 927, 928, 929, 920, 921, 922, 923, 924, 925, 926, 927, 928, 929, 930, 931, 932, 933, 934, 935, 936, 937, 938, 939, 930, 931, 932, 933, 934, 935, 936, 937, 938, 939, 940, 941, 942, 943, 944, 945, 946, 947, 948, 949, 940, 941, 942, 943, 944, 945, 946, 947, 948, 949, 950, 951, 952, 953, 954, 955, 956, 957, 958, 959, 950, 951, 952, 953, 954, 955, 956, 957, 958, 959, 960, 961, 962, 963, 964, 965, 966, 967, 968, 969, 960, 961, 962, 963, 964, 965, 966, 967, 968, 969, 970, 971, 972, 973, 974, 975, 976, 977, 978, 979, 970, 971, 972, 973, 974, 975, 976, 977, 978, 979, 980, 981, 982, 983, 984, 985, 986, 987, 988, 989, 980, 981, 982, 983, 984, 985, 986, 987, 988, 989, 990, 991, 992, 993, 994, 995, 996, 997, 998, 999, 990, 991, 992, 993, 994, 995, 996, 997, 998, 999, 1000, 1001, 1002, 1003, 1004, 1005, 1006, 1007, 1008, 1009, 1000, 1001, 1002, 1003, 1004, 1005, 1006, 1007, 1008, 1009, 1010, 1011, 1012, 1013, 1014, 1015, 1016, 1017, 1018, 1019, 1010, 1011, 1012, 1013, 1014, 1015, 1016, 1017, 1018, 1019, 1020, 1021, 1022, 1023, 1024, 1025, 1026, 1027, 1028, 1029, 1020, 1021, 1022, 1023, 1024, 1025, 1026, 1027, 1028, 1029, 1030, 1031, 1032, 1033, 1034, 1035, 1036, 1037, 1038, 1039, 1030, 1031, 1032, 1033, 1034, 1035, 1036, 1037, 1038, 1039, 1040, 1041, 1042, 1043, 1044, 1045, 1046, 1047, 1048, 1049, 1040, 1041, 1042, 1043, 1044, 1045, 1046, 1047, 1048, 1049, 1050, 1051, 1052, 1053, 1054, 1055, 1056, 1057, 1058, 1059, 1050, 1051, 1052, 1053, 1054, 1055, 1056, 1057, 1058, 1059, 1060, 1061, 1062, 1063, 1064, 1065, 1066, 1067, 1068, 1069, 1060, 1061, 1062, 1063, 1064, 1065, 1066, 1067, 1068, 1069, 1070, 1071, 1072, 1073, 1074, 1075, 1076, 1077, 1078, 1079, 1070, 1071, 1072, 1073, 1074, 1075, 1076, 1077, 1078, 1079, 1080, 1081, 1082, 1083, 1084, 1085, 1086, 1087, 1088, 1089, 1080, 1081, 1082, 1083, 1084, 1085, 1086, 1087, 1088, 1089, 1090, 1091, 1092, 1093, 1094, 1095, 1096, 1097, 1098, 1099, 1090, 1091, 1092, 1093, 1094, 1095, 1096, 1097, 1098, 1099, 1100, 1101, 1102, 1103, 1104, 1105, 1106, 1107, 1108, 1109, 1100, 1101, 1102, 1103, 1104, 1105, 1106, 1107, 1108, 1109, 1110, 1111, 1112, 1113, 1114, 1115, 1116, 1117, 1118, 1119, 1110, 1111, 1112, 1113, 1114, 1115, 1116, 1117, 1118, 1119, 1120, 1121, 1122, 1123, 1124, 1125, 1126, 1127, 1128, 1129, 1120, 1121, 1122, 1123, 1124, 1125, 1126, 1127, 1128, 1129, 1130, 1131, 1132, 1133, 1134, 1135, 1136, 1137, 1138, 1139, 1130, 1131, 1132, 1133, 1134, 1135, 1136, 1137, 1138, 1139, 1140, 1141, 1142, 1143, 1144, 1145, 1146, 1147, 1148, 1149, 1140, 1141, 1142, 1143, 1144, 1145, 1146, 1147, 1148, 1149, 1150, 1151, 1152, 1153, 1154, 1155, 1156, 1157, 1158, 1159, 1150, 1151, 1152, 1153, 1154, 1155, 1156, 1157, 1158, 1159, 1160, 1161, 1162, 1163, 1164, 1165, 1166, 1167, 1168, 1169, 1160, 1161, 1162, 1163, 1164, 1165, 1166, 1167, 1168, 1169, 1170, 1171, 1172, 1173, 1174, 1175, 1176, 1177, 1178, 1179, 1170, 1171, 1172, 1173, 1174, 1175, 1176, 1177, 1178, 1179, 1180, 1181, 1182, 1183, 1184, 1185, 1186, 1187, 1188, 1189, 1180, 1181, 1182, 1183, 1184, 1185, 1186, 1187, 1188, 1189, 1190, 1191, 1192, 1193, 1194, 1195, 1196, 1197, 1198, 1199, 1190, 1191, 1192, 1193, 1194, 1195, 1196, 1197, 1198, 1199, 1200, 1201, 1202, 1203, 1204, 1205, 1206, 1207, 1208, 1209,

The shaft 21 is similarly supported in roller bearings 67 and 68, the latter of which is carried in a bracket 69 detachably secured by bolts 70 to the casting 11. The object of using the detachable brackets 59 and 69 is to give access to the ends of the shafts 22 and 21 for changing the threaded rolls 24 and 23 when threads of different sizes, forms and pitches are to be rolled in the blanks. The inner members of the roller bearings 58 and 68 are held by nuts 65 and 75, respectively, formed with holes adapted to be engaged by a suitable tool to enable the bearings to be released when the shaft ends are opened up for changing the rolls 24 and 23. Each roll 23 and 24 is mounted on a taper sleeve, 61 and 71, respectively, fitting on a taper 64 and 74, respectively, on its shaft, and locked by a nut 62 and 72, respectively. The rolls are fixed on their sleeves by nuts 63 and 73. For rolling right-handed screw threads, the roll 24 is made slightly larger than the roll 23, generally from ten-thousandths of an inch to thirty-thousandths of an inch greater in diameter, so as to turn at a slightly greater surface speed for imparting the travel to the blanks 25 as they pass into the gap between the rolls. A difference in diameter of about twenty-thousandths of an inch has been found suitable, but the amount varies with the depth of thread to be rolled and the time required for rolling it and finishing it in the blanks. The rolls 24 and 23 are formed with multiple start threads, having say eight or ten starts for a coarse pitch, to thirty or more starts for a fine pitch, depending on the sizes of the rolls, their length, and the thread to be formed. The rolls need only differ from standard rolls hitherto used in thread-rolling machines in that one roll is of slightly greater diameter than the other for the purpose already indicated.

Referring again to Figure 4B, it is seen that provision is made for imparting a small amount of longitudinal movement to the shaft 21. A ball-bearing collar 76 connects the end of shaft 21 to a stub shaft 77 which does not turn but is capable of imparting longitudinal motion to shaft 21 through the ball bearing collar. The shaft 77 and a threaded sleeve 78 fitting thereon are both keyed by a feather 79 to the bracket 80 bolted to the end of the housing which surrounds the gear 32 and ball bearings 53. The bracket 80 carries a casting 81 which houses a worm wheel 82 formed as a nut to work on the threaded sleeve 78 and which is held against longitudinal movement by the end of bracket 80 and a shoulder in casting 81. The worm 83 gearing with wheel 82 is fixed on a spindle 84 provided with a milled adjusting head 85. Figures 2 and 3, by means of which head the worm wheel 83 can be adjusted with accuracy for setting the sleeve 78 which limits the movement of shaft 77, and therefore of shaft 21, towards the right in Figure 4B. The shafts 21 and 77 can still be moved toward the left, however, and for this purpose a piston 86 is fixed on the end of the stub shaft 77, said piston working in a cylinder in the casting 81, whose end is closed by a plate 87. Two pipes, 88 and 89 for conveying liquid under pressure, are connected to said cylinder at opposite ends thereof. When a thread-rolling operation begins, pressure is applied through pipe 88 to the left side of piston 86 holding the collar 76, shaft 77 and shaft 21 in the position shown, which will be the correct position in relation to the threads on roll 24 for

commencing the rolling operation on a blank somewhat toward the right of the plane through the axes of the rolls as seen in Figure 6. As the blank moves toward the gap, the relative position will change slightly, and the fluid pressure on the left hand face of piston 86 is therefore relieved as soon as the threads on the rolls have gripped the blank effectively, thus allowing the shaft 21 to shift slightly toward the left. The thread-rolling operation is complete when the blank is in the central position of Figure 6, and after a few turns of the blank in that position, it is polished and ready for ejection. This is effected by applying fluid pressure through pipe 89 to the right hand end of piston 86, causing the shaft 21 to make a short axial movement toward the left in Figures 4A and 4B, this movement being permitted by the splines sliding through worm wheel 32 and by the inner members of the roller bearings 57 and 58 which are free to move in that direction. The relative movement between the two rolls 23 and 24 exerts a pressure on the flanks of the threads rolled on the blank, the effect of which is to expel the blank instantly. The expelled blank rolls over the surface of the lower roll 23 and over the adjustable tray 90 which delivers it through a slot in the column 38. There are, in fact, two trays 90 and 91, which are separately adjustable, the tray 91 supporting the part of the blank which projects beyond the ends of the rolls and which may be the head or other part of a screw.

The blanks are fed down a chute 92 provided at its lower or discharge end with spring blades 93 at the front of said chute and a gap at the back of said chute through which a pusher 94 passes. This pusher moves forward toward the gap between the rolls 23 and 24, at first quickly and then at a slower rate until the blank impelled by the pusher is effectively gripped by the threads of the rolls, the pusher 94 having advanced to the position 94' shown in dotted lines in Figure 6. From this point onwards it is the difference in superficial speed of the upper and lower rolls which advances the blank into and just past the gap. The blank would tend to remain too long at the gap and its thread might be spoiled if it were not expelled quickly from the gap, and the longitudinal or axial movement of the lower roll 23 insures this rapid expulsion. The chute 92 is adjustable and interchangeable with chutes of other sizes for blanks of different dimensions, being secured by bolts 95 engaging in slotted lugs 96.

The pusher is advanced by a piston 97 (Figure 7) in a cylinder 100, to the end of which cylinder liquid is admitted under pressure by a port at 99. In Figure 7, for simplicity, the piston is shown as being pressed back by a spring 106A acting against the liquid pressure, but in the actual machine, as seen in Figure 1, the pusher has a rack 101 engaging over a pinion 102 on a shaft 103, and this shaft extends forwardly, as seen in Figure 3, to carry another pinion 104, Figure 6, meshing with a rack bar 105 below it. This rack bar 105 is shaped as a plunger to slide in a cylinder 107, its end being recessed to accommodate the spring 106 which bears against an abutment on a screw stem 109. This stem is adjustable in the end plate 108 and is locked in any setting by lock nut 110. The rack bar 105 normally bears at its other end against a screw stop 111 which is adjustable to limit the return movement of the pusher 94 under the action of spring 106. In the example illustrated, the pinion 104 is, in

fact, smaller than the pinion 102 (allowing for differences in scale between Figures 6 and 1), the ratio being 1:2½, so that for say 1 inch movement of the rack bar 105 toward the right in Figure 6, the pusher 94 moves 2½ inches toward the gap between the rolls. This movement against the resistance of spring 106 is effected by liquid pressure acting upon the piston 97 in cylinder 100, while the pusher 94 is advanced at first quickly to feed a blank 25, and then slowly to push the blank into the gap between the rolls. When the liquid pressure is relieved, the spring 106 returns the pusher 94 to its retracted position as shown in Figure 6, whereupon a further blank 25 falls in front of the pusher ready for the next feed.

As the size of the blanks 25 may vary, and the height of the centre of the gap between the rolls 23 and 24 is adjusted to correspond, so the height at which the chute 92 is set and at which the pusher 94 operates should be adjustable. The chutes 92 can be made with their slots 96 at the proper height for each, but the pusher requires raising to half the height of the gap between the rolls 23 and 24 so that it may be centred with the middle of the gap. This result is attained by mounting the casting 112, which contains the cylinders 100 and 107 together with the pusher and rack mechanism, so that said casting can be raised and lowered in guides on the face of the column 50, by means of a screw stem 113 which works in a screw socket in the casting 11, and is adjusted by a bar inserted in holes in a disc 114. The casting 112 is clamped in its adjusted position by bolts 115 extending through slots in the column 50. A nozzle 116 discharges cutting compound over the blank at the gap between the rolls 23 and 24 when the machine is in operation. The sequence of operations in the machine is controlled electrically through electromagnetic contactors which operate valves in a hydraulic system, and it will be most convenient to describe the control system mainly with reference to the diagram of Figure 7, although most of the parts referred to can be seen in the different figures from 1 to 6, in their actual positions. Three-phase current is supplied through terminals 120 to three-phase contactors 121 and 122, which contactors include holding-on solenoids 128, 129 and 130 respectively. The contactor 121 controls the circuit of motor 12 and contactor 122 controls the circuit of a motor 133 mounted on top of an oil tank 134 in the base casting 10 (Figure 1). Motor 133 drives two pumps 131 and 132 which draw oil through pipes 135 and 136, respectively, from tank 134 and deliver it through pipes 137 and 138, respectively. The pump 131 delivers oil through a high pressure relief valve 139 to a four-way valve 140, while pipe 138 delivers oil through an adjustable pressure relief valve 141 to another four-way valve 142. Valve 140 is controlled by two solenoids 143 and 144, and valve 142 is controlled by a single solenoid 145. One pressure outlet from valve 140 leads through pipe 89 to the end of cylinder 81 for displacing the roll 23 longitudinally when a rolled blank is to be ejected. The other pressure outlet of valve 140 leads through pipe 146 to a mechanically operated valve 147, and through pipe 148 to a regulatable pressure valve 149, whose adjusting disc 150, with a pointer and scale for fine setting, is seen in Figure 1. Both valves 147 and 149 lead to the inlet port 99 of cylinder 100 whose piston 97 advances the pusher 94. Valve 147 allows a relatively fast flow of oil

which advances the pusher 94 rapidly at first, until a cam surface at 151 depresses a roller 152 on the head of a push rod 153 (Figure 1) which is guided in its vertical movement in a lug beside cylinder 100. This push rod 153 has a screw coupling in it at 154 whereby its length can be adjusted, and its lower end below the casting 11 carries a shoe 155 which bears on a roller 156 on the operating stem of valve 147. The depression of the stem of valve 147 stops flow from left to right through this valve, leaving the oil to be delivered to the cylinder 100 only through valve 149, which valve 149 is set to give a much slower delivery for advancing the pusher 94 slowly while the blank 25 is being thrust into the gap and gripped by the threads of rolls 23 and 24. The pusher 94 follows up the blank as it is gripped and as its metal is displaced by the rolls 23 and 24 until it is certain that the feed will continue without assistance from the pusher, whereupon the pusher recedes as described hereinafter. In Figure 7, the cam 151 and roller 152 are shown, but for simplicity the roller is shown as actuating the stem of valve 147 directly. The four-way valve 142 controlled by a solenoid 145 leads to pipe 88 and to the inner end of piston 86 in cylinder 81 for admitting pressure oil to keep the member 76 against the end of member 78 as seen in Figure 4B.

The end of cylinder 100 is connected to a valve 157 with a pressure adjustment at 158, this valve serving to operate a contact maker 159 in the circuit of relay 127 when a certain pressure is exceeded in the head of cylinder 100. Each of the valves 139, 140, 141, 142, 147, 149 and 157 has a return to tank 134 indicated by an arrow head below the valve. In each case of valves 139, 141, 147, 149 and 157, these returns are opened automatically when a certain pressure is exceeded, but the outlet to tank at 160 on valve 140, and the outlets to tank 161 and 162 of valve 142, are positively controlled by these valves. Several switches with start and stop buttons are provided as shown in the contactor circuits. The start button 163 and stop button 164 of contactor 121, serve to start and stop the motor 12. Numeral 165 designates a reversing switch in the motor circuit by which the motor 12 may be caused to rotate in either direction. This reversing action is required to enable the machine to roll either right-handed or left-handed threads on the blanks 25. When left-handed threads are to be rolled, the large diameter roll should be on the lower shaft 21 and the lower diameter roll on the upper shaft 22, so that the higher surface speed of the lower roll will then determine the travel of the blank through the gap. In the normal operation of rolling right-hand threads, it is the upper roll 24 which is the larger as already stated. Start button 166 and stop button 167 operating the contactor 122 control the circuit of motor 133 which drives the pumps 131 and 132. The slide of pusher 94 carries an adjusted screw pin 168 which operates a release button 169 in the circuit of contactor 125, this button being of the spring-controlled type which, when operated, springs over to close contacts at 170, as shown in dotted lines in the diagram, Figure 7, for closing the circuit of contactor 126. The box 178, Figure 1, containing the switch mechanism 169 and 170, is mounted on a fixed cross bar 179, and the slide of the pusher 94 has a screw adjuster 180, the adjusted end of which abuts against the cross bar 179 in the position to stop the pusher after it

has operated the push button 169. An adjustable screw pin 171 (Figure 3) which moves with the collar 76 and piston 86, serves to operate a stop button 172 in the circuit of contactor 121. The slide of pusher 94 carries another adjusted screw pin 173, Figure 7, which operates a start button 174 in a parallel circuit with a button 176 for operating contactor 125 when the feed of blanks from chute 92 is to be automatic. Start button 176 and stop button 177 control the circuit of contactor 125 when the cycle of operations in rolling threads on blanks is to be controlled for one blank at a time instead of being automatic.

The electric connections and contactors are conveniently situated on the back of a door 181 in the base casting 10, Figure 1, with the start and stop buttons 163 and 164 for the motor 12 on the front, and also the buttons 166 and 167 for the pump 133, and buttons 176 and 177 for contactor 125. Button 176 is used for starting, and 177 for stopping, the feed of blanks 25, whether the supply is automatic or not.

It will be convenient now to trace out the operation of the circuits, contactors and valves for a working cycle. The start buttons 163 and 166 are depressed to start the motors 12 and 133, respectively, in operation, so that the rolls 23 and 24 are rotating at their correct speeds, and the pumps 131 and 132 are circulating oil, while all the contactors except 121 and 122 are de-energised. The oil from pump 131 is returned at low pressure to tank 134 through relief valve 139 and port 160 of valve 140 which is then open. The oil from pump 132 passes via relief valve 141, and four-way valve 142 to pipe 88 and the inner face of piston 86, so maintaining a pressure sufficient to hold the collar 76 against member 78, in which position the roll 23 is held firmly in its right-hand end position ready to start rolling the thread into a blank 25. Excess oil from pump 132 returns to tank 134 via return outlet of relief valve 141. When the start button 176 is pressed, the contactor 125 is energised, causing solenoid 143 to be energised and setting the four-way valve 140 in the position in which oil from pump 131 and relief valve 139 passes through pipe 146, valve 147 and port 99 to cylinder 100, pressing piston 97 and pusher 94 toward the left in the diagram. The pusher takes forward a blank 25 and moves rapidly up to the point where the blank is about to touch rolls 23 and 24. At this stage, the cam 151 presses down roller 152 and closes the valve 147. The oil now passes through valve 149 which is set to give a slow delivery of oil, still to the same port 99, advancing the pusher 94 slowly but with a substantial pressure behind it, sufficient to force the blank between the threads of the rolls 23 and 24, and to start the rolling of the threads into the blank. The rolls now grip the blank between them and move it forward due to the slightly higher peripheral speed of roll 24, causing it to move up to the central plane of the roll axes. Before this occurs, however, the oil pressure in cylinder 100 will have risen rapidly as the resistance to forward movement of pusher 94 increases due to the work being done on the blank by the rolls, and the pressure so produced reaches a value, at which time the valve 157 operates to close contact 159 and energise contactor 127, which, in turn, energises solenoid 145. This solenoid moves valve 142 to a position in which the inner face of piston 86 is open through pipe 88 and return port 162 to the tank 134, while the oil reaching valve

142 via relief valve 141 is returned to the tank through return port 161. The roll 23 is now free to adjust itself longitudinally to keep its threads in correct engagement with the threads being rolled in the blank as this latter passes into the plane of the rolls.

The pusher 94 continues to move forward even after the blank is gripped by the rolls, until screw 168 pushes button 169 thus breaking the circuit 10 of contactor 125 and closing, at 170, the circuit of contactor 126. The solenoid 143 is thus de-energised and solenoid 144 is energised, moving valve 140 to a position in which pressure oil is delivered through pipe 89 to the outer end of cylinder 81 thus moving the roll 23 axially in the direction which causes the rolled blank to be ejected over the tray 90. The oil from the other side of piston 86 returns to tank 134 via port 162 of valve 142, and oil from cylinder 100 returns to tank 134 via valve 147 which allows free flow in the reverse direction as soon as port 160 of valve 140 connects pipe 146 to tank 134, which occurs when solenoid 144 is energised.

As the piston 86 moves forward in cylinder 81, screw 171 operates push button 172 to break the circuit of contactor 126, thus causing solenoid 144 to be de-energised, and also de-energising contactor 127 and solenoid 145, which allows valve 142 to return to its starting position. All 30 the solenoids 143, 144 and 145 are now de-energised. As the pusher 94 moves back under the action of spring 106 (or 106A in the diagram, Figure 7), the screw 173 operates push button 174 thus closing the circuit of contactor 125 and so starting a fresh cycle of operations, in which valve 140 is energised by solenoid 143 causing oil to be delivered by pipe 146, valve 147 and port 99 to the cylinder 100, and causing the pusher 94 to advance to thrust forward the next blank from the chute 92.

It will be realised, of course, that the electric controls and the hydraulic operating circuits are only an example of one method of operating the machine to roll threads into blanks, and that other means of operation and control might be provided which would effect the feed and passage of a blank towards and through the gap between the rolls while a thread is being impressed upon it. It is essential in all cases that one of the rolls should have a slightly higher peripheral speed than the other for determining the advance of a blank into and across the gap, and this is most conveniently provided for by making one roll slightly larger in diameter than the other as already explained. The machine can be used for rolling threads on any articles such as bolts, screws, taps and so forth which can be fed as blanks into the machine.

We claim:

1. A machine for rolling screw threads into blanks comprising a pair of shafts and means for supporting them at a predetermined distance apart, a pair of thread rolling dies one slightly larger in diameter than the other, means for mounting one of said thread rolling dies on each of said shafts, means for driving said shafts simultaneously to move the surfaces of said thread rolling dies in opposite directions at their zone of nearest approach with the surface of the larger thread rolling die moving slightly faster than the surface of the other thread rolling die, means for feeding blanks to be threaded into the gap between said thread rolling dies at one side of said dies, means for preventing longitudinal movement of one of said shafts and of the thread

rolling die mounted thereon, means for permitting longitudinal movement of the other of said shafts and of the thread rolling die mounted thereon, means for moving said last-mentioned shaft and die longitudinally with respect to said first-mentioned shaft and die, and means for timing such last-mentioned movement to effect the same immediately upon the completion of the thread rolling operation when the blank is passing through the narrowest portion of the gap between the thread rolling dies, such timed longitudinal movement rapidly ejecting the threaded blank laterally from between said dies.

2. A machine for rolling screw threads into blanks comprising a pair of opposed thread rolling dies each formed with multiple start threads of the same pitch, one of said dies being slightly greater in diameter than the other, means for supporting said dies at a predetermined distance apart, means for rotating said opposed dies at the same angular velocity and in opposite directions with the surface of the die of greater diameter moving at a slightly greater superficial speed than the surface of the other, means for feeding blanks to be threaded towards the gap between said dies at the side at which the surface of the die of greater diameter is approaching the gap between said dies, means for preventing longitudinal movement of one of said dies, means for permitting longitudinal movement of the other of said dies, means for moving said last-mentioned die longitudinally with respect to said first-mentioned die, and means for timing such last-mentioned movement to effect the same immediately upon the completion of the thread rolling operation when the blank is passing through the narrowest portion of the gap between the thread rolling dies, such timed longitudinal movement rapidly ejecting the threaded blank laterally from between said dies.

3. A machine for rolling screw threads into blanks comprising a pair of opposed thread rolling dies each formed with multiple start threads of the same pitch, one of said dies being slightly greater in diameter than the other, means for supporting said dies at a predetermined distance apart, means for rotating said opposed dies at the same angular velocity and in opposite directions with the surface of the die of greater diameter moving at a slightly greater superficial speed than the surface of the other, means for feeding blanks to be threaded towards the gap between said dies at the side at which the surface of the die of greater diameter is approaching the gap between said dies, means for preventing longitudinal movement of one of said dies, means for preventing longitudinal movement of the other of said dies at the start of the thread rolling operation, means for permitting longitudinal movement of the last-mentioned die after the start of the thread rolling operation, means for moving said last-mentioned die longitudinally with respect to said first-mentioned die, and means for timing such last-mentioned movement to effect the same immediately upon the completion of the thread rolling operation when the blank is passing through the narrowest portion of the gap between the thread rolling dies, such timed longitudinal movement rapidly ejecting the threaded blank laterally from between said dies.

4. A machine for rolling screw threads into blanks comprising a pair of opposed thread rolling dies each formed with multiple start threads of the same pitch, one of said dies being slightly

greater in diameter than the other, means for supporting said dies at a predetermined distance apart, means for rotating said opposed dies at the same angular velocity and in opposite directions with the surface of the die of greater diameter moving at a slightly greater superficial speed than the surface of the other, means for feeding blanks to be threaded towards the gap between said dies at the side at which the surface of the die of greater diameter is approaching the gap between said dies, means for preventing longitudinal movement of one of said dies, an abutment adjacent the other of said dies adapted for engagement by said die to prevent longitudinal movement of said die in one direction, hydraulic pressure means adapted to maintain said last-mentioned die in engagement with said abutment at the start of the thread rolling operation, means for permitting release of said hydraulic pressure and movement of said last-mentioned die away from said abutment after the start of the thread rolling operation, hydraulic pressure means for moving said last-mentioned die longitudinally with respect to said first-mentioned die and away from said abutment, and means for timing the last-mentioned movement to effect the same by said last-mentioned hydraulic pressure means immediately upon the completion of the thread rolling operation when the blank is passing through the narrowest portion of the gap between the thread rolling dies, such timed longitudinal movement rapidly ejecting the threaded blank laterally from between said dies.

5. A machine for rolling screw threads into blanks comprising a pair of spaced, parallel shafts, a pair of opposed thread rolling dies, means for securing one of said dies on each of said shafts, means supporting one of said shafts in a fixed position laterally, a laterally-adjustable slide, means for supporting the other of said shafts on said slide, locking means for fixing said slide in a position of lateral adjustment determining the gap between said dies, means for driving said shafts simultaneously to move the surface of the dies mounted thereon in opposite directions, one of said thread rolling dies being slightly greater in diameter than the other, means for feeding blanks to be threaded toward the gap between said dies at the side thereof where the surface of the larger of said dies is approaching the gap between said dies, means for preventing longitudinal movement of one of said shafts and of the thread rolling die mounted thereon, means for permitting longitudinal movement of the other of said shafts and of the thread rolling die mounted thereon, means for moving said last-mentioned shaft and die longitudinally with respect to said first-mentioned shaft and die, and means for timing such last-mentioned movement to effect the same immediately upon the completion of the thread rolling operation when the blank is passing through the narrowest portion of the gap between the dies, such timed longitudinal movement rapidly ejecting the threaded blank laterally from between said dies.

6. A machine for rolling screw threads into blanks comprising a pair of spaced, parallel shafts and power operating means therefor, a pair of thread rolling dies one slightly larger in diameter than the other, means for securing one of said dies on each of said shafts, means supporting one of said shafts in a fixed position laterally, means for adjusting the other of said shafts laterally and for locking it in its position of adjustment to thereby determine the gap between said

11

dies, a pusher, means for guiding said pusher in its movement towards the gap between said dies, means for feeding blanks in front of said pusher, hydraulic operating means for said pusher, means for preventing longitudinal movement of one of said shafts and of the die mounted thereon, means permitting longitudinal movement of the other of said shafts and of the die mounted thereon, hydraulic operating means for moving the last-mentioned shaft and die longitudinally with respect to the first-mentioned shaft and die, controlling valves for both of said hydraulic operating means, and means for effecting timed operation of said valves to advance and withdraw said pusher, and to subsequently effect longitudinal movement of said last-mentioned shaft and die by said hydraulic means immediately upon the completion of the thread rolling operation when the blank is passing through the narrowest portion of the gap between the thread rolling dies, such timed longitudinal movement rapidly ejecting the threaded blank laterally from between said dies.

7. A machine for rolling screw threads into blanks comprising a pair of spaced, parallel shafts, a pair of thread rolling dies, means securing said dies in opposed relation on said shafts, driving mechanism adapted to rotate said shafts of rotation, means for adjustably supporting said shafts and for locking them in fixed position laterally to determine the width of the gap between the dies on said shafts, means for feeding blanks to be threaded toward the gap between said dies at one side of said dies, means for preventing longitudinal movement of one of said shafts and of the die mounted thereon, means for permitting longitudinal movement of the other of said shafts and of the die mounted thereon, means for moving said last-mentioned shaft and die longitudinally with respect to said first-mentioned shaft and die, and means for timing such last-mentioned movement to effect the same immediately upon the completion of the thread rolling operation when the blank is passing through the narrowest portion of the gap between the thread rolling dies, such timed longitudinal movement rapidly ejecting the threaded blank laterally from between said dies.

8. A machine for rolling screw threads into blanks comprising a pair of spaced, parallel thread rolling dies, means for supporting said dies in fixed relation laterally to determine the gap between said dies, means for simultaneously rotating said dies, means for feeding a blank to be threaded toward the gap between said dies at one side thereof, means for preventing longitudinal movement of one of said dies, means permitting longitudinal movement of the other of said dies, and automatic mechanism adapted to sequentially operate said blank feeding means for advancing a blank toward the gap between said dies, then to withdraw said blank feeding means, and finally to move said last-mentioned die longitudinally with respect to said first-mentioned die, said longitudinal movement of said last-mentioned die being effected immediately upon the completion of the thread rolling operation when the blank is passing through the narrowest portion of the gap between the thread rolling dies to rapidly eject the threaded blank laterally from between said dies.

9. A machine for rolling screw threads into

12

blanks comprising a pair of thread rolling dies and means for supporting the same at a predetermined distance apart in parallelism, one of said dies being of slightly greater diameter than the other, means for simultaneously rotating said dies, a pusher adjacent the gap between said dies, means for feeding blanks one at a time in front of said pusher, an hydraulic piston and cylinder, means connecting said piston with said pusher, spring returning means for said piston, means for preventing longitudinal movement of one of said dies, means for permitting longitudinal movement of the other of said dies, hydraulic mechanism, means connecting said hydraulic mechanism with said last-mentioned die to effect longitudinal movement of said die upon actuation of said hydraulic mechanism, a plurality of hydraulic control valves and electrical means of control therefor adapted to control the supply of the hydraulic fluid to said piston and cylinder and to said hydraulic mechanism in such sequence as to cause, first, the advance of said pusher, then to permit of the return of said pusher by said spring returning means, then to cause longitudinal movement of said last-mentioned die, and then to return said last-mentioned die to its starting position.

10. A machine for rolling screw threads into blanks comprising a pair of opposed thread rolling dies, means for supporting said dies at a predetermined distance apart in parallelism, one of said dies being of slightly greater diameter than the other, a pusher adjacent the gap between said dies, means for feeding blanks one at a time in front of said pusher, means for advancing and returning said pusher, means for simultaneously rotating said dies, means for preventing longitudinal movement of one of said dies, means for permitting longitudinal movement of the other of said dies, means for moving said last-mentioned die longitudinally with respect to the first-mentioned die, and automatic timing mechanism adapted to sequentially control the advance and return of said pusher, and the longitudinal movement of said last-mentioned die with respect to said first-mentioned die after said pusher has been advanced and returned, the movement of said last-mentioned die being effected immediately upon the completion of the thread rolling operation when the blank is passing through the narrowest portion of the gap between the dies and serving to rapidly eject the threaded blank laterally from between said dies.
